UNITED STATES PATENT OFFICE.

CHRISTOPHER STRAUB, OF EAST ELMHURST, NEW YORK, ASSIGNEE, BY MESNE ASSIGNMENTS, TO ASTORIA IMPORTING AND MANUFACTURING CO. INC.

CONTROL MECHANISM FOR VENEER-CUTTING MACHINES.

Application filed June 1, 1925. Serial No. 34,082.

This invention relates to control mechanism for veneer cutting machines and has for its particular object to provide devices for automatically advancing the cutter or 5 knife toward the log from which the slices of veneer are removed after each cut. The invention is particularly applicable to veneer slicing machines of the type disclosed in the U. S. patents to William H. Williams 10 No. 269,363 dated December 19, 1882, and No. 651,287 dated June 5, 1900, wherein the log is moved transversely of the knife edge and after each cut the knife edge is advanced preparatory to the next cut. The objects 15 and advantages of the invention and the means for their attainment will be more apparent from the following detailed description of a preferred embodiment thereof illustrated in the accompanying drawings 20 in which:

Figure 1 is a view in side elevation showing such details of the veneer slicing machine as is necessary to an understanding of the application of the invention thereto 25 as well as the automatic means for advancing the knife after each cut.

Figure 2 is a plan view showing the machine illustrated in Figure 1 and the invention applied thereto.

Figure 3 is a view taken in the plane indicated by the line 3—3 in Figure 2 and looking in the direction of the arrows and showing the means for actuating the control mechanism from the reciprocating bed of 35 the veneer slicing machine.

Figure 4 is a view taken in the plane indicated by the line 4—4 in Figure 1 and looking in the direction of the arrows and showing details of the clutch mechanism 40 involved.

Figure 5 is a view taken in the plane indicated by the line 5—5 in Figure 4 and showing further details of the clutch mechanism.

Referring to Figure 1 a log *a* from which slices of veneer are to be taken is illustrated as secured to the face of the stay log *b* which is capable of reciprocation in a vertical plane along guides or ways *x* in well known manner, the reciprocation being effected by means of pitmen and cranks, for instance actuated from a reciprocating bed *c*. The knife or cutter *d* is carried upon a knife carrier *d'* adapted to be moved toward or

from the log *a* along tracks *d*² mounted upon the base *e*. At either side of base *e* there are mounted rotatable worm shafts *f* and carried with the knife carrier *d'* are interiorly threaded members *d*³ through which the worm shafts *f* pass. The worm shafts *f* carry at one end thereof bevel pinions *f'* which mesh with bevel gears *f*² carried upon a transversely extending shaft *f*³ upon the end of which a hand wheel *f*⁴ is mounted. Rotation of the hand wheel *f*⁴ causing rotation of the shaft *f*³ and bevel pinions *f'*² will cause synchronous rotation of the bevel pinions *f'* and worm shafts *f* which in turn mesh with the interiorly threaded members *d*³ and cause the knife carrier *d'* to reciprocate along the tracks *d*². So much of the machine as has just been described is well known in the art and forms no part of the present invention. Automatic control devices or actuating devices obviating the requirement of manual operation of the hand wheel *f*⁴ comprise the subject matter of the present invention and will now be described in detail.

Shaft *f*³ also carries a bevel pinion *f*⁵ 80 constantly in mesh with a bevel pinion *g* carried upon the shaft *g'*. Upon the shaft *g'* there is mounted a pulley *g*² driven as by the belt *g*³ from a motor, not shown, by which the shaft *g'* may be rotated in one direction to cause the knife carrier *d'* to travel from one extreme position to the other. Step by step movement of the carrier whereby the knife is advanced after each slice of veneer is cut, preparatory to 90 making a second cut, is also effected by rotation of the shaft *g'*. Slidable upon the shaft *g'* is a sleeve *h* having a peripheral groove *h'* and formed with a wedge horn *h*². Entering the groove *h'* are lugs carried 95 upon a bifurcated member *i'* carried with a lever *i*² pivoted at one end as at *i*³ to the frame of the machine and at the other end connected to a link *i*⁴ secured to a hand lever *i*⁵. By throwing the lever *i*⁵ in one 100 direction or the other about its pivot *i*⁶, the sleeve *h* may be moved longitudinally of the shaft *g'*. Mounted upon the end of the track *d*² is a bell-crank lever *j*² one arm of which is secured to the link *i*⁴, the other end being in the path of movement of the knife carrier so that when the knife carrier has 105 reached the end of its inward stroke it will

engage with the end of the bell-crank lever i^5 causing movement of the link i^4 to slide the sleeve h relative to shaft g' . Freely rotatable upon shaft g' is an annular member j formed outwardly with ratchet teeth j' and inwardly upon the side adjacent the sleeve h with a clutch surface j^2 adapted to be engaged by a split ring k keyed to the shaft g' . The split ring k is adapted to be expanded by the wedge horn h^2 to cause the split ring to engage the clutch surface j^2 and in this manner cause the rotation in unison of the ratchet j and shaft g' . An inverted U-shaped frame l is adapted to surround a portion of the ratchet j and carries a plurality of pawls l' so spaced that at least one of them is at all times adapted to engage the ratchet teeth j' to prevent rotation of the ratchet in one direction. Adjacent the frame l there is disposed a housing m loosely mounted upon the shaft g' and carrying a plurality of feeding pawls m' at least one of which is at all times also adapted to engage the ratchet teeth j' . Housing m is preferably annular in form and, encircling the same for approximately half its perimeter, is a chain n secured at one end to a spring or other yielding device n' . The other end of the chain n is connected to an arm o rigidly carried upon a shaft o' also carrying rigidly a second arm o^2 having preferably a roller o^3 at its end. Shaft o' is disposed above the reciprocating bed c transversely thereof and an adjustable cam surface c' is adapted to be engaged by the roller o^3 on the end of the arm o^2 . In order to vary the inclination of the cam devices c' any convenient devices may be adapted, that disclosed in the illustrated embodiment taking the form of a threaded rod c^2 . It will be apparent that as the bed c reciprocates the cam c' will cause the rotation of the arm o^2 and with it the shaft o' about the axis of the shaft thereby causing the arm o to draw the chain against the action of the spring n' and rotate the housing m about the shaft g' . Rotation of the housing is transmitted through the pawls m' to the ratchet j whereby ratchet and housing are caused to rotate together about the shaft g' . Thus as the bed c moves in one direction, as to the left in Figure 3, the rotation of the shaft o' causes the chain n to rotate housing m and ratchet j in a clockwise direction. When the bed c has reached the limit of its stroke and started in the return direction the spring n' will tend to draw the chain in the opposite direction thereby rotating housing m in a counterclockwise direction. In this instance, the ratchet j does not rotate with the housing the lock pawls l' insuring against such rotation.

There is, of course, the possibility of rotative movement of the ratchet j in a coun-

terclockwise direction (Fig. 5) when the housing m is rotating under the action of the spring n' since the locking pawls l' prevent rotation only in one direction i. e. clockwise. To insure against such relative movement, immediately upon the release of the feeding pawls m' , a brake is provided which positively engages the ratchet j at that instant. This brake is illustrated in Figure 4 as taking the form of a wooden brake shoe p carried with an arm p' pivoted at one end in the frame l and connected by link p^2 with a bell crank p^3 . Bell crank p^3 may be rotated about the pivot p^4 in any convenient manner. In the illustrated embodiment it is disclosed as adjustably connected by one arm to a link p^5 connected with the arm o . So soon as the arm o starts to return in a clockwise direction about the axis o' the brake shoe will be caused to engage the ratchet.

The operation of the device is as follows: Movement of the bed c along the track c^3 , which is effected in any convenient manner as by a pitman connected to a crank rotated by a motor or the like (not shown), causes the relative movement by other connections of the stay log b along the track x . The knife carrier d' is brought to its initial position either manually through the hand wheel f^4 or by means of the electric motor rotating the pulley g^2 preparatory to taking the initial slice of veneer from the log a . After the stay log is moved downwardly along the track x and a slice of veneer is removed from the log and the log returned to the position indicated in Figure 1, the knife edge d must be moved forwardly a distance equal to the thickness of a slice of veneer preparatory to the next cut. This movement has heretofore been effected by rotation of the hand wheel f' in a manner which will be understood from the foregoing description. In order to affect automatic step by step movement of the knife carrier d' the shaft g' is clutched to the ratchet j by means of the expandable split ring k which is expanded and brought into clutching engagement with the interior surface j^2 by means of the wedge horn h^2 which is moved forwardly into engaging position with the split ring by throwing the lever i^5 toward the right in Figure 1. Movement of the bed c toward the left in Figure 3 initiates the upward movement of the stay log b and as the bed c moves toward the left the cam member c' comes in contact with the arm o^2 , (the wheel o^3 permitting the arm to travel easily over the surface of the cam c') to rotate the arm o^2 in a counterclockwise direction about the axis of the shaft o' . Being carried rigidly with the shaft o' the counterclockwise rotation of the arm o^2 causes a similar counterclockwise rotation of the arm o , also carried rigidly with the

- shaft o' and such rotation of the arm o m by the chain n a sprocket wheel may be incorporated therewith, with which the causes a movement of the chain n toward the right in Figure 3 to cause a clockwise chain engages. It will thus be seen that an effective automatic device is provided which causes the 70 step by step movement of the knife carrier through predetermined distances in synchronism with the movement of the stay log.
- 10 shaft g' by reason of the wedge horn h^2 which is engaged within the expansible member k , at this time tightly engaging the inner surface j^2 of the ratchet. Movement, therefore, of the arm o in a counterclockwise direction causes appropriate rotation of the shaft g in a clockwise direction which in turn effects the rotation of the worm shafts f to move the knife carrier d' toward the right in Figure 1. 75
- 15 The effective radial length of the arm o and the various component elements of the clutch mechanism disclosed in Figures 4 and 5 are such that when the bed c has reached the limit of its stroke toward the left (Figure 3) the bed will have been moved a distance equivalent to the thickness of the slice of veneer to be cut from the log. At this instant the brake p is applied to the ratchet to insure against undesirable movement of the bed which would affect the exactness of the next cut. This braking action as has been pointed out hereinbefore is also effected by the rotation of the arm o in a 80 counterclockwise direction. As the bed c starts toward the right the pawls l' engaging the ratchet teeth j' prevent relative movement of the ratchet as the housing m is rotated in a counterclockwise direction, under the action of the spring n' . The movement of the arm o in clockwise direction releases the tension of the chain n and permits it to be drawn under the action of the spring n' to rotate the housing m in counterclockwise direction preparatory to 85 the next feeding step. As the knife carrier d' reaches the forward limit of its stroke it engages the end of the crank lever i^2 which effects the withdrawal of the wedge horn and the unclutching of the actuating mechanism from the shaft g' thus preventing any further movement of the knife carrier. The knife carrier may then be returned to the outward limit of its stroke preparatory to inserting a new log by the rotation of the 90 shaft g' through the belt driven pulley g^2 .
- 95 The degree of movement of the knife carrier and thereby the thickness of the slice of veneer removed at each stroke is controlled by the cam c' which is affected by the set devices c^2 . A pointer q carried with the shaft o' is adapted to gage the extent of movement of the arm o by travel over a scale q' and thus an accurate indication of the setting required is afforded.
- 100 105 110 115 120 125 130
- 65 To facilitate the rotation of the housing 135
- Various modifications may be made in the particular form taken by the associated instrumentalities whose operation is initiated by the stay log cutting means and no limitation is intended by the foregoing description or accompanying illustrations but it is 80 to be understood that any type of mechanism which will effect intermittent movement of the knife carrier dependent upon movement of the stay log is within the scope 85 of the invention.
- What I claim is:
1. In a veneer slicing machine having a movable stay log, the combination with actuating means therefor including a reciprocating bed and a relatively movable knife carrier, of means to move the carrier comprising a rotatable shaft, means to rotate said shaft in one direction dependent upon the actuating means for the stay log, means to prevent rotation of the shaft in the opposite direction, and clutching means between the shaft and the means to rotate the same. 90
  2. In a veneer slicing machine having a movable stay log, actuating means therefore 100 and a relatively movable knife carrier, of means to move the carrier comprising a rotatable shaft, means to rotate said shaft in one direction dependent upon the actuating means for the stay log, means to prevent rotation of the shaft in the opposite direction, clutching means between the shaft and the means to rotate the same, and a brake shoe to engage the ratchet. 105
  3. In a veneer slicing machine having a movable stay log, actuating means therefore 110 and a relatively movable knife carrier, of means to move the carrier comprising a rotatable shaft, a ratchet wheel carried with the shaft and rotatable with respect thereto 115 and formed with an annular recess in one side thereof, an expansible ring keyed to the shaft within the recess means, to expand the ring to frictionally engage the ratchet, a relatively stationary frame, a pawl carried with the frame and engageable with the ratchet teeth, an annular housing rotatable freely on the shaft, a pawl carried with the housing and engaging the shaft, and means to rotate the housing dependent upon movement of the stay log. 120
  4. In a veneer slicing machine having a movable stay log, actuating means therefore 125 including a reciprocating bed and a relatively movable knife carrier, of means to

- move the carrier comprising a rotatable shaft, a ratchet wheel carried with the shaft and rotatable with respect thereto and formed with an annular recess in one side thereof, an expandible ring keyed to the shaft within the recess, means to expand the ring to frictionally engage the ratchet, a relatively stationary frame, a pawl carried with the frame and engageable with the ratchet teeth, an annular housing rotatable freely on the shaft, a pawl carried with the housing and engaging the shaft, and means to rotate the housing comprising cam devices carried with the reciprocating bed, a rotatable arm actuated by said cam devices and a chain connected to said arm and encircling said housing.
5. In a veneer slicing machine having a movable stay log, actuating means therefore including a reciprocating bed and a relatively movable knife carrier, of means to move the carrier comprising a rotatable shaft, a ratchet wheel carried with the shaft and rotatable with respect thereto and formed with an annular recess in one side thereof, an expandible ring keyed to the shaft within the recess, means to expand the ring to frictionally engage the ratchet, a relatively stationary frame, a pawl carried with the frame and engageable with the ratchet teeth, an annular housing rotatable freely on the shaft, a pawl carried with the housing and engaging the shaft, means to rotate the housing comprising cam devices carried with the reciprocating bed, a rotatable arm actuated by said cam devices, a chain connected to said arm and encircling said housing, and a brake shoe to engage the ratchet and operative connections between the brake shoe and the rotatable arm.
6. In a veneer slicing machine having a movable stay log, actuating means therefore including a reciprocating bed and a relatively movable knife carrier, of means to move the carrier comprising a rotatable shaft, a ratchet wheel carried with the shaft and rotatable with respect thereto and formed with an annular recess in one side thereof, an expandible ring keyed to the shaft within the recess, means to expand the ring to frictionally engage the ratchet, a relatively stationary frame, a pawl carried with the frame and engageable with the ratchet teeth, an annular housing rotatable freely on the shaft, a pawl carried with the housing and engaging the shaft, means to rotate the housing comprising cam devices carried with the reciprocating bed, a rotatable arm actuated by said cam devices, a chain connected to said arm and encircling said housing and secured at its end to a yielding device, and a brake shoe to engage the ratchet and operative connections between the brake shoe and the rotatable arm.
7. In a veneer slicing machine having a movable stay log, the combination with actuating means therefor and a relatively movable knife carrier, of means to move the carrier comprising a rotatable shaft, a toothed wheel freely rotatable on said shaft, clutching means between said toothed wheel and said shaft, a relatively stationary pawl engageable with said toothed wheel, a housing freely rotatable about said toothed wheel, a pawl carried with the housing and engageable with the toothed wheel, and means to rotate the housing.
8. In a veneer slicing machine having a movable stay log, the combination with actuating means therefor and a relatively movable knife carrier, of means to move the knife carrier comprising a rotatable shaft, a ratchet wheel freely rotatable on said shaft, clutching means between said toothed wheel and said shaft, a relatively stationary pawl engageable with said ratchet, a housing freely rotatable about said ratchet, a pawl carried with the housing and engageable with the ratchet, and means to rotate the housing dependent upon said actuating means.
9. In a veneer slicing machine having a movable stay log, the combination with actuating means therefor including a reciprocating bed and a movable knife carrier comprising a shaft, means to cause rotation of the shaft in one direction and operable connections between said means and the actuating means for the stay log effective upon predetermined movement of the stay log.
10. In a veneer slicing machine, in combination, a stay log, actuating means therefore including a reciprocating bed, a movable knife carrier, operable connections between the knife carrier and the reciprocating bed, and means to control the degree of movement of the knife carrier dependent upon movement of the bed.
11. In a veneer slicing machine, in combination, a stay log, actuating means therefore including a reciprocating bed, a movable knife carrier, operable connections between the knife carrier and the reciprocating bed, means to control the degree of movement of the knife carrier dependent upon movement of the bed, comprising a cam carried with the bed, and yielding devices to maintain said connections in operative relation with the cam.
12. In a veneer slicing machine, in combination, a stay log, actuating means therefore including a reciprocating bed, a movable knife carrier, connections between the knife carrier and reciprocating bed operative upon movement of the bed in one direction, and means to control the degree of movement of the knife carrier dependent upon movement of the bed.
13. In a veneer slicing machine having a

- movable stay log, the combination with actuating means therefor including a reciprocating bed and a relatively movable knife carrier, of means to move the carrier including a shaft and operative connections between the bed and shaft to rotate the shaft in one direction comprising cam devices carried with the bed, a rotatable arm actuated by said cam devices and a chain connected to said arm and encircling said housing.
14. In a veneer slicing machine having a movable stay log, the combination with actuating means therefor including a reciprocating bed and a relatively movable knife carrier, of means to move the carrier including a shaft and operative connections between the bed and shaft to rotate the shaft in one direction comprising cam devices carried with the bed, a rotatable arm actuated by said cam devices, a chain connected to said arm and encircling said housing, and means to vary the cam.
15. In a veneer slicing machine having a movable stay log, the combination with actuating means therefor including a reciprocating bed and a relatively movable knife carrier, of means to move the carrier including a shaft, and operative connections between the bed and shaft to rotate the shaft in one direction comprising cam devices carried with the bed, a rotatable arm and brake mechanism effective upon predetermined movement of the bed to control rotation of said shaft.
16. In a veneer slicing machine having a movable stay log, the combination with actuating means therefor including a reciprocating bed and a relatively movable knife carrier, of means to move the carrier including a shaft and operative connections between the bed and shaft to rotate the shaft in one direction including cam devices carried with the reciprocating bed, a rotatable arm actuated by said cam devices and a chain connected to said arm and operatively connected with the shaft to rotate the same and being secured at its end to a yielding device.
17. In a veneer slicing machine having a movable stay log, the combination with actuating means therefor including a reciprocating bed and a relatively movable knife carrier, of means to move the carrier comprising a rotatable shaft, a ratchet wheel carried with the shaft and rotatable with respect thereto and formed with an annular recess in one side thereof, an expansible ring keyed to the shaft within the recess, means to expand the ring to frictionally engage the ratchet, a relatively stationary frame, a pawl carried with the frame and engageable with the ratchet teeth, an annular housing rotatable freely on the shaft, a pawl carried with the housing and engaging the shaft, and means to rotate the housing comprising cam devices carried with the reciprocating bed, a rotatable arm actuated by said cam devices, and a connection between the housing and the arm to rotate said housing.
18. In a veneer slicing machine having a movable stay log, the combination with actuating means therefor including a reciprocating bed and a relatively movable knife carrier, of means to move the carrier comprising a rotatable shaft, a ratchet wheel carried with the shaft and rotatable with respect thereto and formed with an annular recess in one side thereof, an expansible ring keyed to the shaft within the recess, means to expand the ring to frictionally engage the ratchet, a relatively stationary frame, a pawl carried with the frame and engageable with the ratchet teeth, an annular housing rotatable freely on the shaft, a pawl carried with the housing and engaging the shaft, and means to rotate the housing comprising cam devices carried with the reciprocating bed, a rotatable arm actuated by said cam devices, a connection between the housing and the arm to rotate said housing, and a flexible connection between the arm and the housing.
19. In a veneer slicing machine having a movable stay log, the combination with actuating means therefor including a reciprocating bed and a relatively movable knife carrier, of means to move the knife carrier including a rotatable shaft and operative connections between the bed and shaft to rotate the shaft in one direction comprising cam devices carried with the bed, a shaft transverse to the direction of movement of the bed, an arm carried with the shaft and contacting with the cam, a second arm carried with the shaft, flexible connections between the second arm and the first named shaft, and yielding means against which said second arm operates.

This specification signed this 27th day of May A. D. 1925.

CHRISTOPHER STRAUB.
